BY Siggett Siggett

ATTORNEY

UNITED STATES PATENT OFFICE.

EUGENE L. HOWE, OF CLEVELAND, OHIO, ASSIGNOR TO THE EBERHARD MANUFACTURING COMPANY, OF SAME PLACE.

DESIGN FOR A CARRIAGE-STEP.

SPECIFICATION forming part of Design No. 18,720, dated November 6, 1888.

Application filed September 27, 1888. Serial No. 286,600. Term of patent 7 years.

To all whom it may concern:

Be it known that I, EUGENE L. HOWE, a citizen of the United States, residing at Cleveland, in the county of Cuyahoga and State of Ohio, have invented and produced a new and original Design for Carriage-Steps, of which the following is a specification, reference being had to the accompanying drawings, forming part thereof.

10 Figure 1 is a plan. Fig. 2 is an elevation in transverse section through the center of the step.

A represents the body of the step, the same being flat and circular in plan. The step is provided with a raised border consisting of a series of upwardly-projecting ribs, *a*, in radial order. The central portion of the step is provided with a series of concentric ribs, *b*, within which is shown a sunken star, *c*. The step is

neat and tasty in appearance, and by reason 20 of the raised ribs, substantially as indicated, the foot is not liable to slip on the step.

What I claim is—

The design for a carriage-step herein shown and described, the same consisting of a circular step provided with a series of ribs set radially and constituting a border for the step, the central portion of the step being provided with a series of concentric ribs, and a sunken star at the center of the step.

In testimony wherof I sign this specification, in the presence of two witnesses, this 20th day of April, 1888.

EUGENE L. HOWE.
